GOLF CLUB

Filed Nov. 17, 1928

UNITED STATES PATENT OFFICE

HENRY J. KLUTHO, OF JACKSONVILLE, FLORIDA

GOLF CLUB

Application filed November 17, 1928. Serial No. 320,187.

My invention relates to a golf club or driving device for a miniature golf ball, by the use of which golf may be played in-doors or in other limited areas. The present invention is an improvement over that shown in my previous application #254,740, filed February 16, 1928.

Among the objects of the invention is to provide a device of this character of simplified construction, wherein a different type of spring mechanism is employed, all as will be hereinafter more particularly specified and claimed.

Referring to the accompanying drawings, which are made a part hereof and on which similar reference characters indicate similar parts,

Figure 1 is a front elevation illustrating one application of my invention,

Figure 2, a fragmentary part sectional part side elevational view of the lower portion of the structure of Fig. 1,

Figure 3, a similar view of the upper portion,

Figure 4, a front elevation of the modified form of head, and

Figure 5, a section on the line 5—5 of Fig. 4.

In the drawings reference character 40 indicates a handle shaft formed of hollow tubing which as in my previous invention corresponds to the handle of an ordinary golf club and has secured to its lower end a pair of diverging feet 41 which form a two-point support for the device during its use.

In the upper end of the handle shaft is secured a wooden plug 42 held in place by brad fasteners 43, and said wooden plug serves to re-enforce the tubular shaft and to prevent said shaft from collapsing. A hand hold 44 is fitted over the end of the handle and gives the device the appearance of the handle of a conventional golf club. On the lower portion of the tubular shaft or handle is mounted a bracket 45 which forms a pivotal support for a swingable arm 46 which carries a driving head or golf club 47 at its lower end. The bracket 45 is adjustably slidable upon the shaft 40 and is held in fixed position on the shaft by means of a set screw 48 which forms the pivot for the arm 46.

The club 47 has a reduced end 49 fitted into the end of the tubular arm 46, and the club is removably held in the arm by means of a spring 50 which has its upper end fixed to the arm and has its lower end projecting through an aperture in the arm and an aperture in the reduced portion 49 of the club. This construction permits a quick removal and replacement of clubs.

The arm 46 is free to swing on its pivot 48 and in order to give the arm 46 the necessary or desired swing I provide a bracket 51 upon the arm 46 and to said bracket I pivot a toggle lever 52 which is provided with an off-set portion at the end remote from the bracket 51 in order to space the extremity of the toggle lever in a plane away from the swinging arm 46. A pin 53 is carried in the off-set end of the toggle lever 52, and such pin extends through and is movable in opposed slots 54 in the handle or shaft of the club so that when the pin is moved longitudinally in the slots 54 it will be caused to swing the golf club. Means is provided for reciprocating the pin in its slots which comprises a plunger 55 which extends up through the handle 40 and has its upper end pivoted with another pin 56 located in similar opposed slots 57 in the handle and which extends through an external sleeve 58 having a finger piece or manipulating element 59. The end of the plunger extends beyond the pivot 56 and forms a centering element for a helical spring 60, the lower end of which bears against the pin 56, and the upper end of which bears against the wooden plug 42. The tendency of the spring will be to maintain the plunger in its lowermost position with the toggle lever 52 in such position that the swing arm 46 which carries the golf club is parallel to the handle 40. When the member 49 is pulled upwardly toward the hand hold 44 the plunger will move the pin 53 toward the upper end of the slots 54 and cause the toggle lever 52 to swing the arm 46 on its pivot 48 away from the position at which it is shown in Figures 1 and 2, whereupon if the manipulating element 59 is released the spring 60 having been compressed will drive the club back to its original position and thus perform 100

a driving action corresponding to the driving stroke of a golf club.

In Figs. 4 and 5 I have shown a modified form of head which is rotatable for bringing into selective use different forms of driving members or clubs. In lieu of the club 47 having its reduced shank fitting into the tubular arm 46 I provide a tubular body 61 upon which is mounted a circular head 62 said head forming a base for a rotatable head member 63. The rotatable head member 63 is provided with a recess 64 for the reception of a spring 65, one end of which bears against the inner end of the recess 64 and the other end of which bears against the washer 66 on the under side of the head of a bolt 67 which extends through the rotary head 63 and is threaded into the base 62, said screw also serving to hold the base on its supporting sleeve 61. Co-operating projections and recesses 68 and 69 are provided in the base and rotary head respectively in order to maintain the rotary head in the desired position. The rotary head 63 may be provided with any desired number of driving members 70, in the present instance three being shown for the purpose of illustration, any one of which may be brought to depending operative position in alignment with the supporting arm 46 by which it may be caused to perform a driving operation. On account of the structure described the head may be rotated, the spring 65 permitting the members 62 and 63 to separate sufficiently to permit them to be brought to the proper position.

It will be obvious to those skilled in the art that various changes may be made in my device without departing from the spirit of the invention, and I, therefore, do not limit myself to what is shown in the drawings and described in the specification, but only as set forth in the appended claims.

Having thus fully described my said invention, what I claim as new and desire to secure by Letters Patent, is:

1. A device for playing golf comprising a handle, a driving member pivoted on said handle, a plunger supported longitudinally of the handle, spring means associated with the plunger, adapted to be compressed when the plunger is moved longitudinally in one direction, and adapted when released to move the plunger longitudinally in the other direction, and a lever connecting the plunger and driving member for swinging the driving member upon the longitudinal movement of the plunger, substantially as set forth.

2. A device for use in playing indoor golf, comprising a hollow handle, a rocker arm pivoted on said handle, a driving member detachably carried by the rocker arm, a spring housed in said hollow handle, means for compressing said spring, and means connected to the rocker arm in a manner to be operated by the recoil of the spring from its com-

pressed position, whereby the rocker arm and driving member are swung in an arc simulating the driving action of a golf club, substantially as set forth.

3. A golf club for playing indoor golf comprising a hollow handle, a spring housed in the upper end of the hollow handle, a plunger in the hollow handle beneath the spring and urged downwardly by the spring, a rocker arm pivoted on the handle, a driving member carried by the rocker arm, a longitudinal slot in the lower end of the handle, a pin extending through said plunger reciprocable in said slot, and a lever connecting the rocker arm and pin and adapted to be urged in an arc by the reciprocation of the pin in the slot, whereby when the plunger and pin are moved upwardly against the action of the spring the rocker arm and driving member will be swung away from the depending position, and when the plunger is released the spring will force the same upwardly to swing the rocker arm and driving member in a manner simulating the driving action of a golf club, substantially as set forth.

4. A device of the character described comprising a handle, a driving member pivotally mounted on said handle, operating means disposed longitudinally of the handle, resilient actuating means within said handle associated with the operating means adapted to be compressed when the operating means is moved longitudinally in one direction and adapted when released to move the operating means longitudinally in the other direction, and means connecting the operating member and driving member for swinging the driving member in a manner simulating the driving action of a golf club upon the longitudinal movement of the operating member, substantially as set forth.

In witness whereof, I have hereunto set my hand at Jacksonville, Florida, this 15th day of November, A. D. nineteen hundred and twenty-eight.

HENRY J. KLUTHO.
